United States Patent Office.

CHARLES J. WOOLSON, OF CLEVELAND, OHIO.

Design No. 2,625, dated April 16, 1867.

DESIGN FOR A STOVE DOOR.

The Schedule referred to in these Letters Patent and making part of the same.

TO ALL WHOM IT MAY CONCERN:

Be it known that I, CHARLES J. WOOLSON, of Cleveland, Ohio, have invented a new and useful Design for the Doors of Stoves.

My invention consists in constructing the central and main portions of stove doors of a series of bars, with openings between, so arranged as to form an ornamental design and afford a pleasant view of the fire.

Figure 1, in the drawing, affords a front view, and

Figure 2 a back view of the same.

What I claim as new, and desire to secure by Letters Patent, is—

The design for stove doors, as herein designated and represented.

CHARLES J. WOOLSON.
